UNITED STATES PATENT OFFICE.

WESLEY S. BOWSER, OF ST. LOUIS, MISSOURI.

MEANS FOR OPERATING AWNINGS.

SPECIFICATION forming part of Letters Patent No. 708,693, dated July 1, 1902.

Application filed January 20, 1902. Serial No. 90,489. (No model.)

To all whom it may concern:

Be it known that I, WESLEY S. BOWSER, a citizen of the United States, residing in the city of St. Louis, in the State of Missouri, have 5 invented certain new and useful Improvements in Means for Operating Awnings, of which the following is a full, clear, and exact description, reference being had to the accompanying drawings, forming part of this 10 specification.

My invention relates to means for raising and lowering that class of awnings attached to and adapted to be wound on rollers, the construction of the device being such that the 15 roller may be quickly and efficiently rotated to wind the awning thereonto or permit the unwinding of the awning.

The invention consists in features of novelty hereinafter fully described, and pointed 20 out in the claim.

Figure I is a side elevation illustrating my device. Fig. II is a view partly in front elevation and partly in vertical section. Fig. III is a vertical cross-sectional view taken on line 25

III III, Fig. I.

1 designates the roller of an awning, having a shaft 2, that is supported in suitable hang- 30 ers at the desired elevation.

3 is a fragment of the awning on the roller. 35 4 designates a bevel-gear fixed to the shaft 2 at the end of the roller 1, and located beside said gear is a swing-socket 5, loosely mounted on the shaft and held from endwise movement thereon by a collar 6, secured to the shaft by a set-screw 7.

8 is a vertical shaft having its upper end loosely positioned in the swing-socket 5, so as to be capable of turning freely therein.

9 is a bevel-pinion held to the vertical shaft 40 8 by a set-screw 10 and having its teeth ar- ranged in meshing engagement with the teeth of the gear 4 on the roller-shaft 2.

11 designates a box adapted to be mounted on the wall of the building to which the awning is applied and through the upper portion 45 of which the vertical shaft 8 passes, so as to rotate in the box, the shaft being upheld by a supporting-collar 12, containing a set-screw 13. Fixed to the lower end of the vertical 50 shaft 8, within the box 11, is a bevel-pinion 14, that is held to said shaft by a set-screw 15.

16 is a bevel-pinion that meshes with the

bevel-pinion 14 and is mounted on a shaft 17, horizontally positioned in the box 11 and adapted to receive a crank 18, by which it may 55 be turned. On the shaft 17, within the box 11, is a ratchet 19, that is adapted to receive the engagement of a pawl 20, pivotally connected to the box 11.

In the practical use of the device the shaft 60 17 is rotated through the medium of the crank 18, and by the intermeshing of the bevel-pi- 65 nions 14 and 16 rotation is imparted to the vertical shaft 8, and consequently to the bevel-pinion 9, carried thereby. In the rotation of 70 the vertical shaft its upper end turns freely in the swing-socket 5, and through the intermeshing connection between the bevel-pinion 9 and the bevel-gear 4 rotation is imparted to the roller-shaft 2 to wind the awning 3 on 75 the roller 1 or permit its unwinding therefrom. The swing-socket 5 being loosely mounted on the roller-shaft hangs freely sus- 80 pended. Therefore the roller-shaft may turn freely therein and the coinciding parts oper- 85 ate with freedom and ease of action.

In many buildings to which awnings are ap- 80 plied, such as those containing store-rooms, there are projections or lintels that protrude beyond the faces of the walls a very consid- 85 erable distance in some instances and to which it is necessary to attach the roller or a roll-awning, and it is the intention of my in- 90 vention to provide an awning-operating con- struction that may be so mounted as to set in 95 wall-facings irrespective of the projection to which the awning-roller is applied. It is ap- 100 parent that in awning-operating means to be universally adjustable upon buildings hav- ing more or less projecting wall portions, as stated, it is highly essential that the con- struction of the awning-operating means be such that the vertical operating-shaft may be placed in varying degrees of uprightness or inclination with respect to the building-wall, and this my construction provides for. It will be seen from the drawings and the fore- 105 going description that the swing-socket 5 en- ables the mounting of the shaft 2 of the awning-roller in any position above the operat- 110 ing-gearing beneath it, either in a vertical plane above it or to one side of a vertical plane, inasmuch as the swing-socket may be moved on the roller-shaft to position it so

that it will properly receive the upper end of the vertical operating-shaft irrespective of whether the roller-shaft is directly above the lower support of the vertical operating-shaft 5 or at one side of a vertical plane from said support. In this connection it is only necessary to properly mount the lower end of the vertical operating-shaft in its support in a manner that will enable it to stand upright 10 or extend upwardly in an inclined direction.

I claim as my invention—

In a device of the class described, the combination of a roller, a shaft on which said roller is mounted, a bevel-gear fixed to said

shaft, a vertical shaft, means for rotating said vertical shaft, a bevel-pinion adjustably fixed to said vertical shaft and arranged for engagement with said bevel-gear, a swing-socket loosely mounted on said roller-shaft and in which the upper end of said vertical shaft is 20 loosely seated to rotate freely therein, and a collar secured to said roller-shaft to hold said socket from endwise movement, substantially as described.

WESLEY S. BOWSER.
